UNITED STATES PATENT OFFICE

CHARLES S. PARKER, OF MERIDEN, CONNECTICUT, ASSIGNOR TO THE CHARLES PARKER COMPANY, OF MERIDEN, CONNECTICUT, A CORPORATION

SHELF BRACKET

Application filed January 30, 1932. Serial No. 589,798.

This invention relates to an improvement in shelf-brackets and particularly to brackets for supporting shelves of glass or similar material, commonly used in bathrooms and other places.

Various means for holding the glass in place have been devised, but in most cases, they are unsightly and impose a strain upon the shelf. The object of this invention is to provide means for holding the shelf firmly in the bracket with means which are entirely hidden from view, and the invention consists in the construction as hereinafter described and particularly recited in the claims.

5 In the accompanying drawing:

Fig. 1 is a side view, partly in section, of a shelf-bracket constructed in accordance with my invention;

Fig. 2 is a top view of the same;

20 Fig. 3 is a sectional view on the line 3—3 of Fig. 1; and

Fig. 4 is a perspective view of the clamp, detached.

In carrying out my invention, I employ 25 a bracket comprising a wall-plate 10 adapted to be secured to the wall or other surface in any desired manner. Projecting from the base is a horizontal arm 11 and also projecting from the base, above the arm, is a 30 short lug 12, the under face of which is slightly beveled.

The outer end of the arm terminates in a hook 13 formed with a pocket 14 and with a clearance-opening 15 through the under 35 edge of the arm. Located in the pocket is a clamping-block 16 into the lower end of which a screw 17 extends, this screw being inserted through the clearance-opening 15.

The inner face 18 of this clamp is prefer-40 ably beveled. A shelf 19 of glass or other suitable material, and formed with beveled edges 20, is inserted beneath the lug 12 and hook 13, and when located, the clamping-block 16 is drawn downward by the screw 17 45 until it contacts with the forward edge of the shelf and crowds it rearward beneath the lug 12 and firmly clamps the shelf to the arm 11, it being understood that a bracket is arranged near each end of the shelf.

50 This device firmly holds the shelf in posi-

tion without imposing any undue strain upon the shelf.

I claim:

In a shelf-bracket, the combination with a base, serving as a wall-plate, of an arm 55 projecting outwardly therefrom at a right angle thereto, a retaining-lug carried by the base at a point directly above the said arm and spaced apart therefrom, an upwardly- and-inwardly-extending hook located at the outer end of the arm and containing an inwardly-and-downwardly-opening chamber 60 closed at its top, bottom and sides, a vertically-movable L-shaped clamping-member located in the said chamber, and a screw passing upwardly through the outer end of the arm into the said chamber and engaging with the clamp therein whereby the same may be drawn downwardly upon the edge of the glass entered into the said hook.

65 In testimony whereof, I have signed this specification.

CHARLES S. PARKER.
